MULTI-PURPOSE BIN

Manus Mudde, Berkel-Enschot, Netherlands, assignor to Dart Industries, Inc., West Bend, Wis.

Filed Jan. 22, 1973, Ser. No. 325,915

Claims priority, application Switzerland Aug. 4, 1972

Term of patent 14 years

Int. Cl. D7—07

U.S. Cl. D7—76

FIG. 1 is a view in side elevation of a multi-purpose bin embodying my new design;

FIG. 2 is a top plan view thereof;

FIG. 3 is a front or rear elevation thereof; and

FIG. 4 is a bottom plan view of FIG. 3.

I claim:

The ornamental design for a multi-purpose bin, substantially as shown and described.
